UNITED STATES PATENT OFFICE.

WILLIAM M. PRESTON, OF ROXBURY, NEW YORK, ASSIGNOR TO HIMSELF
AND JESSE A. SECOY, OF SAME PLACE.

IMPROVEMENT IN ALARM-BELLS.

Specification forming part of Letters Patent No. 125,328, dated April 2, 1872.

SPECIFICATION.

To all whom it may concern:

Be it known that I, WILLIAM M. PRESTON, of Roxbury, in the county of Delaware and State of New York, have invented certain new and useful Improvements in Alarm-Bells; and I do hereby declare that the following is a full, clear, and exact description thereof, reference being had to the accompanying drawing and to the letters of reference marked thereon, which form a part of this specification.

The nature of my invention consists in the construction and arrangement of a "door-bell," and also in the construction and arrangement of a device to be attached to the door, so that when desired the door-bell will answer the purpose of an alarm-bell, as will be hereinafter more fully set forth.

In order to enable others skilled in the art to which my invention appertains to make and use the same, I will now proceed to describe its construction and operation, referring to the annexed drawing, in which—

Figure 1 is a front view of my entire door-bell, and Figs. 2 and 3 are detached views of parts thereof.

A represents an L-shaped bar or plate attached to the door-casing, and to the outer end of which the bell B is secured in any suitable manner. To the bar A is pivoted a plate, C, which carries upon a projecting arm the hammer D, and is held in proper position by a spring, E. One end of this spring is attached to the bar A, and the other end to the plate C, and is completely hid by the bell. A stud, a, on the plate C is, by a rod, b, connected with a lever, G, in the door-casing, and this lever is, by another rod, d, connected with another lever, H, projecting on the outside, so that by simply bearing down upon the outer end of the lever H the bell will be sounded. It will also be noticed that the hammer D will give two blows on the bell, one when the lever

H is pressed down, and the other as soon as the pressure is taken off, by means of the spring E.

This bell, or any other door-bell attached to the door-casing, may be used as an alarm-bell by means of the following simple device. To the inner side of the door near the edge is attached a plate, I, and to this is pivoted a bar, J, having upon its outer end an inclined or cam-shaped projection, e, which may be set so as to strike a similar projection, f, upon the hammer-plate C, and thus sound the bell both in opening and closing the door. The inner end of the bar J is forked; and through the same to the plate I is pivoted a key, K, having on its under side a cam, i, which operates on the prongs of said fork. By turning this key K in one direction the cam i will set the bar J so that the projections e and f will engage with each other, while by turning it in the other direction the projection e will be thrown away from the projection f, and thus the bell fail to be sounded in opening and closing the door.

Having thus fully described my invention, what I claim as new, and desire to secure by Letters Patent, is—

1. The arrangement of the L-shaped bar A, bell B, pivoted plate C, with hammer D and spring E, all substantially as and for the purposes herein set forth.

2. The combination of the plate I, forked bar J with projection e, and key K with cam i, all constructed and arranged as described, to be used in connection with a projection on the hammer support of a door-bell, substantially as and for the purposes herein set forth.

In testimony that I claim the foregoing as my own I affix my signature in presence of two witnesses.

WM. M. PRESTON.
